UNITED STATES PATENT OFFICE.

EDWARD KENER, JR., OF BUFFALO, NEW YORK.

INCINERATOR.

Application filed February 13, 1924. Serial No. 692,508.

To all whom it may concern:

Be it known that I, EDWARD KENER, Jr., a citizen of the United States, residing at Buffalo, in the county of Erie and State of New York, have invented a new and useful Improvement in Incinerators, of which the following is a specification.

This invention relates to an incinerator which is more particularly designed for use in households or kitchens for the purpose of making it easily possible to consume kitchen refuse and similar material.

It is the object of this invention to provide an incinerator of this character which will completely consume all of the refuse of various kinds which are ordinarily accumulated in a kitchen and burn the same so thoroughly that only dry ashes remain and no perceptible odors escape to the exterior of the incinerator or to the outside of the building, thereby avoiding offense to neighbors as well as to the persons operating the incinerator.

In the accompanying drawings:

Figure 1 is a vertical section of an incinerator constructed in accordance with my invention.

Figure 2 is a horizontal section taken on line 2—2, Figure 1.

Figure 3 is a fragmentary vertical section, on an enlarged scale, taken on line 3—3, Figure 1.

Figure 4 is a fragmentary section, on an enlarged scale, taken on line 4—4, Figure 2.

Figure 5 is a horizontal section taken on line 5—5, Figure 3, looking upwardly.

Figures 6, 7, 8 and 9 are perspective views of parts of the mechanism for mounting the burner and the spreading plate within the combustion chamber so as to permit of reciprocating the same vertically and oscillating the same horizontally.

Similar characters of reference indicate like parts in the several figures.

The numeral 10 represents the combustion chamber or refuse receptacle which is designed to receive the refuse or garbage which is to be burned, this material being introduced through an inlet 12 in the upper part of this chamber, which inlet is normally closed by means of a door 13. Within this chamber is arranged an inner upright side wall 14 which supports the pile of refuse 15 on its side, this wall being pro-

vided throughout its height and at suitable intervals with a plurality of perforations or openings 16.

Adjacent to the outer side of this inner wall is arranged an outer wall 17 which is tight or imperforate and separated or spaced apart from the inner wall 14 so as to form an intervening conduit or space 18 therebetween. This clearance space 18 opens at its upper end into the upper part of the combustion chamber while its lower ends opens into the ash pit 19. This ash pit is separated from the combustion chamber by a grate which is of any suitable or approved construction and surrounded by a rim 20 and which supports the pile of refuse on its underside as well as the pile of ashes resulting from the destruction of this refuse by cremation. Communicating with the upper end of the combustion chamber and preferably extending upwardly from the central part of the top 21 thereof, is a flue or gas discharge pipe 22, whereby the combustion chamber may be connected with a chimney of the building or otherwise extended to the exterior of the building for the purpose of carrying off any non-combustible gases which are generated by the incinerator.

Arranged on the central part of the grate is a bridge 23 which is preferably made hollow and provided centrally on its upper part with an opening 24. Extending upwardly from this bridge is a vertically telescoping burner which is so mounted that the same gradually descends in the same measure as the pile of garbage or refuse is gradually consumed from the top downwardly and therefore becomes less in height. In its preferred construction this telescopic burner consists of a plurality of sections 25, 26, 27 and 28 which are of progressively reduced diameter from the lowermost to the uppermost and slide one within the other in the form of a telescope. The lowermost section 25 of this burner projects upwardly through the opening 24 through the bridge 23 and is provided with an upwardly facing flange or shoulder 29 which is adapted to engage with the underside of the bridge for the purpose of limiting the upward movement of the lowermost burner section and also the remaining sections which are telescopically connected therewith. Each of

the upper burner sections is also provided with an upwardly facing annular shoulder or flange 30 which engages with a downwardly facing shoulder or flange 31 formed 5 on the upper end of the next lower burner section and thereby serves as stopping means which limit the extent which the telescope burner can be distended upwardly or away from the bridge of the grate. The upper- 10 most burner section is provided in different parts of its side with a plurality of gas outlet openings 32 and its upper end is also open so that gas which is supplied to this burner at the lower end issues upwardly and laterally from all directions so that upon 15 igniting the gas which issues from the upper end of this burner the same will play a flame which engages with the upper part of the pile of garbage or refuse in the combustion 20 chamber. This gas is supplied to the lower end of the burner by means of a gas delivery pipe or conduit 33 which is arranged in the ash pit close to the underside of the grate 20 and provided centrally with 25 an upwardly projecting delivery nozzle 34 which directs the gas upwardly into the lower end of the burner, while the outer end of this burner is connected externally 30 of the incinerator with a gas supply pipe 35 which is connected with any suitable source of supply.

Arranged within the upper part of the combustion chamber and adapted to be supported by or rest on the top of the pile of 35 refuse is a spreading plate 36 which is preferably of upwardly dished form. Instead of resting this spreading plate or disk directly upon the pile of refuse, it is provided on its underside with a plurality of spacing ribs 40 37 which extend from the central part of the underside of the spreading plate to the marginal part thereof, the inner end of each of these ribs, however, terminating short of the axis of this spreading plate so as to 45 leave a clear central space on the underside of this plate and each of the spacing ribs also preferably extending for a short distance beyond the marginal edge of the spreading plate and within a short distance of the inner 50 side of the inner wall 15, as shown in Figure 1. This spreading plate is connected with the uppermost section of the burner so that the same rises and falls together, this being preferably effected by means of a link 55 38 which is of T-shaped form and engages its crosspiece with corresponding openings in the upper end of the uppermost burner section while its shank is secured in a central opening in the spreading plate, as shown in 60 Figure 1.

It follows from this construction that whenever the spreading plate is raised or lowered, the telescopic sections of the burner will be extended or nested accordingly and 65 that the height of the burner will therefore

be governed by the vertical position of the spreading plate within the combustion chamber. As the gas burns in a flame against the upper part of the pile of refuse, the same is directed over the top of the same 70 and caused to overspread the pile of refuse by reason of the deflecting or baffling action of the spreading plate 36 which compels this flame to lie close to the top of the pile of refuse and practically come in contact with 75 all parts of this upper surface before it can escape into the upper part of the combustion chamber. The flame therefore not only operates to heat the garbage so as to liberate the gas producing elements therein which 80 results in a gradual cremation of the refuse and a reduction of the same to ashes, but the flame also serves to ignite and burn the combustible gases thus generated before they can escape from the upper part of the combustion chamber to the exterior of the incinerator in the building in which it is installed. This complete destruction of the garbage and the burning of the combustible gases which may be generated prevents the 85 escape of any odor bearing gases to the exterior of the incinerator or of the building and therefore renders the use of the incinerator in cities and other closely built-up quarters unobjectionable. 90

This burning of the garbage or the refuse proceeds gradually from the top of the pile toward the lower end thereof, the operation consisting in first drying the parts of the garbage successively from the top downwardly and as the drying proceeds and gases are given off the same are ignited by the flame of the burner and add their heat thereto in such a way that the successively lower parts of the garbage which are still wet or in a non-combustible condition are also successively heated and dried and converted into a condition of combustibility. As a result of this operation, the garbage itself furnishes a considerable amount of the fuel whereby 105 heat is generated for effecting destruction of the garbage and this process continues from the top of the pile downwardly until the entire mass of garbage is cremated and only a comparatively low pile of ashes remains resting upon the grate from which the same can be discharged into the ash pit below by dumping the grate or otherwise disposing of the same. 110

As the ashes are produced on top of the pile while the garbage is being consumed by the flame of the burner playing against the top of the same, the incinerating operation would be interfered with if the ashes were permitted to remain and means are therefore provided for removing the ashes from the top of the pile at will, so that the flame of the burner will always be able to attack the refuse under the most favorable conditions which will promote rapid and complete 115 120 125 130

destruction thereof. For this purpose the ashes are raked off from the top of the pile of refuse through the openings 16 in the inner side wall so that they enter the clearance space 18 through which they drop by gravity into the ash pit 19 so that they can be subsequently removed from the latter through the ash outlet opening 39 thereof which is normally closed by the door 40.

10 A convenient and practical way of accomplishing this purpose is to utilize the ribs 37 on the underside of the spreading plate 36 as rake teeth or clearing members which ribs upon being oscillated while resting on top of the ashes will cause the latter to be gradually moved or raked off from the top of the pile and discharged laterally outward through the adjacent openings 16 in the inner wall of the combustion chamber, 15 thereby enabling the unconsumed top of the refuse to be always exposed practically free from ashes and thus enable the flames to operate most efficiently on the garbage and gradually consume the same from the 20 top of the pile downwardly to the lower end thereof. This oscillation of the raking ribs 37 is preferably effected by connecting the spreading plate 36 with shaking means which extend to the exterior of the apparatus 25 where they are accessible to an attendant 30 who can thereby operate the ash removing device whenever it is necessary or desirable to do this.

The means for thus agitating or operating 35 the ash removing means are preferably combined with elevating means whereby the spreading plate and the burner sections may be elevated into their uppermost position preparatory to reloading the combustion 40 chamber with a new batch of refuse or garbage, which is to be destroyed. This combined agitating and elevating mechanism is therefore preferably constructed as follows:

45 The numeral 41 represents an upright gear rack which has its upper part arranged within the flue 22 and its lower part within the combustion chamber and has its lower 50 end connected with a lug on the upper central part of the spreading plate 36, as shown in Figures 1 and 3. The teeth of this gear rack are engaged by an elevating gear pinion 55 which is suitably mounted so that upon turning this pinion the rack may be either raised or lowered. This rotary motion may be imparted to the gear pinion by means of a horizontal shaft or rod 43 which is arranged in a segment shaped recess 44 in the top of the combustion chamber and has its inner end connected with the gear pinion 42 while its outer end projects outwardly 60 beyond the side of the combustion chamber and is provided with a hand wheel or handle 45 whereby this shaft and the parts associated therewith may be manipulated by the

attendant. During the operation of the apparatus the descent of the spreading plate 36 together with its ribs 37 and the gear rack 41 descend by gravity inasmuch as the ribs of the spreading plate rest upon the top of the pile and descend in the same measure as this pile is gradually reduced in height as the result of removing the ashes therefrom. The gear rack and gear pinion are so mounted on the upper part of the 70 combustion chamber that the handle 45 and operating shaft 43 may also be utilized for agitating the spreading plate 36 and its shaking ribs 37 by swinging the rod or shaft 43 horizontally back and forth in the pocket 80 or recess 44. In order to permit of this action and still enable the burner plate and parts associated thereto to be raised and lowered without interference, the gear rack 41 is made of angular form in cross section, 85 preferably square, and guided above and below the pinion in guide bushings 46, 47 which are journaled in the upper and lower bearings 48 and 49 arranged above and below the pinion 42 and forming part of a 90 bracket 50 which is mounted on the top of the combustion chamber and extends across the lower end of the vapor outlet flue 22. Each of these bushings 46 and 47 is provided with an annular flange 51, the flange of the 95 upper bushing engaging with a downwardly facing shoulder 52 on the upper bearing and the flange 51 of the lower bushing engaging with an upwardly facing shoulder 100 53 on the lower bearing and each of these bushings being also provided with an axial opening 54 which is square in cross section so that it fits the gear rack 41 and permits the latter to slide in the bushings but compels the same to turn therewith in the bearings 48 and 49. Between the upper and lower bushings 46 and 47 is arranged a yoke 105 54 which has an angular seat 55 which engages with the exterior of the gear rack 41 and permits the latter to slide vertically in 110 this yoke, but compels the same to turn therewith. This yoke bears at its upper and lower ends against the opposing ends of the upper and lower bushings 46 and 47 so that this yoke is held against vertical displacement but is capable of turning with the gear rack.

The gear pinion 43 is arranged between two bearings 56, 56 on the yoke 54 and the inner part of the shaft 43 which carries this pinion is journaled in these bearings 56. By this means a rotation of the operating shaft 43 in one direction or the other will cause the pinion to raise and lower the rack 41 and the spreading plate 36 and parts associated therewith while upon swinging the outer end of the operating shaft horizontally back and forth in the pocket or recess 44, the yoke 54 together with the pinion, rack, spreading plate and ribs 37 115 120 125 130

will be oscillated about a vertical axis, thereby adapting the spreading plate and burner to the varying heights of the pile of refuse in the combustion chamber and also permitting of producing the agitating effect of the spreader and its ribs whereby the ashes are raked off or discharged from the top of the pile, as before described.

In view of the fact that a considerable part of this elevating and agitating mechanism is arranged within the upper part of the combustion chamber and extends upwardly into the gas flue 41, these parts are concealed from view and do not encroach upon any space which is required for other purposes thereby not only simplifying the construction of the apparatus but also rendering the same very neat and attractive in appearance and thus the same is particularly suitable for household use.

In order to permit of holding the elevating and agitating mechanism in place while the spreading plate 36 and parts associated therewith are in their highest position, a locking device is provided which will leave the attendant free to fill the combustion chamber with refuse. This locking mechanism is preferably combined with the elevating and agitating mechanism so that practically no extra parts are required for this purpose. In its preferred form this locking mechanism consists of a locking lug 57 which projects laterally from the lower part of the gear rack, and a locking hook 58 arranged on the underside of the lower bearing 49 of the bracket 50. The relative arrangement of the locking lug 57 and the locking hook 58 is such that upon turning the gear rack into one position, for instance when swinging the operating bar to its extreme right hand position as indicated by full lines in Figure 2, this rack and the parts associated therewith may be raised and lowered freely. When, however, the rack is in its highest position and the lug 57 thereof engages the underside of the lower bracket bearing 49, this lug 57 may be engaged over the hook 58 on the bracket, as shown in Figures 3 and 5, by swinging the operating shaft 43 from the position shown by full lines in Figure 2 to the position shown by dotted lines in the same figure, and thereby turning the gear rack 41 so as to engage its locking lug 57 with the locking hook 58 in the manner described. The spreading plate and the burner may therefore by this means be readily locked in an elevated position so that the attendant can freely introduce a new batch or mass of garbage into the combustion chamber around the burner and underneath the spreading plate, preparatory to again unlocking the gear rack from the bracket and permitting the spreading plate to be lowered together with the burner until this plate again rests by gravity upon the top

of the pile of garbage so that consumption of the same can take place upon again lighting the gas flame and then removing the ashes from time to time in the manner previously described.

In order to permit the operating shaft 43 to be freely rocked horizontally in the recess 44 without liability of gases escaping from the discharge flue 41 into this recess, a collar 61 is provided for connecting the upper end of the combustion chamber and the flue and this collar is provided with a segmental slot 59 which is covered by a curved shutter 60 sliding circumferentially on the periphery of the collar. The operating shaft projects through the slot 59 and through the shutter and the latter moves with the shaft during its horizontal rocking movements but always covers the slot 59 to prevent the escape of any gas.

This incinerator not only permits of completely destroying the garbage in a manner which is practically odorless and yields a minimum of ashes, but the same is also very compact in construction, very neat and attractive in appearance and the several parts can be easily manipulated and are not liable to get out of order.

I claim as my invention:

1. An incinerator comprising a combustion chamber adapted to receive the pile of refuse to be consumed, means for burning the pile of refuse from the top downwardly, and means for removing the ashes from the top of the pile.

2. An incinerator comprising a combustion chamber adapted to receive the pile of refuse to be consumed, means for burning the pile of refuse from the top downwardly, and means for removing the ashes from the top of the pile comprising a disk adapted to engage with the top of said pile, and means for agitating said disk.

3. An incinerator comprising a combustion chamber adapted to receive the pile of refuse to be consumed, means for burning the pile of refuse from the top downwardly, and means for removing the ashes from the top of the pile comprising a disk adapted to engage with the top of said pile, and means for turning said disk about a vertical axis.

4. An incinerator comprising a combustion chamber adapted to receive the pile of refuse to be consumed, means for burning the pile of refuse from the top downwardly, and means for removing the ashes from the top of the pile comprising a disk provided on its underside with ribs extending from the central to the marginal parts of the disk and adapted to engage with the top of said pile, and means for turning said disk about a vertical axis located at the central part thereof.

5. An incinerator comprising a combustion chamber adapted to receive a pile of

- refuse to be consumed, a burner arranged centrally within the combustion chamber and having a vertically movable part adapted to deliver a gas flame toward the upper 5 part of the pile of the refuse, and a disk adapted to rest on top of said pile and connected with said vertically movable burner member and adapted to oscillate about a vertical axis.
- 10 6. An incinerator comprising a combustion chamber adapted to receive a pile of refuse to be consumed and having a perforated side wall, an outer wall arranged around said side wall and spaced therefrom 15 to form an intervening vertical passage, an ash pit arranged below said combustion chamber and communicating with said vertical passage, a burner arranged centrally within the combustion chamber and having 20 a vertically movable part adapted to deliver a gas flame toward the upper part of the pile of the refuse, and a disk adapted to rest on top of said pile and connected with said vertically movable burner member and 25 adapted to oscillate about a vertical axis.
7. An incinerator comprising a combustion chamber adapted to receive a pile of refuse to be consumed and having a perforated side wall, an outer wall separated from 30 said side wall and forming a vertical passage therebetween, an ash pit communicating with said vertical passage, means for delivering a flame against the upper part of the pile of refuse, and means for agitating 35 the top of the pile of refuse and discharge the ashes thereon through the perforations of said side wall from which the same drops through said passage into said ash pit.
- 40 8. An incinerator comprising a combustion chamber adapted to receive a pile of refuse to be consumed, means for burning the pile of refuse from the top of the same downwardly, and oscillating means for removing the ashes from the top of the pile.
- 45 9. An incinerator comprising a combustion chamber adapted to receive a pile of refuse to be consumed, means for burning the pile of refuse from the top of the same downwardly, and means for removing the 50 ashes from the top of the pile comprising an oscillating agitator adapted to engage with the top of the pile.
- 55 10. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile and also capable of being 60 raised and lowered.
- 65 11. An incinerator comprising a combustion chamber adapted to receive a pile of refuse to be consumed, means for burning the pile of refuse from the top of the same
- downwardly, and means for removing the ashes from the top of the pile comprising an oscillating agitator adapted to engage with the top of the pile, and means for raising and lowering said agitator comprising 70 an upright gear rack, a gear pinion meshing with said rack, and an operating shaft connected with said gear pinion.
12. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile, and means for raising and lowering said agitator comprising 75 an upright gear rack, a gear pinion meshing with said rack, and an operating shaft connected with said gear pinion and provided on one side of the combustion chamber with a handle for manipulating the same.
13. An incinerator comprising a combustion chamber adapted to receive a pile of refuse to be consumed, means for burning the pile 80 of refuse from the top of the same downwardly, and means for removing the ashes from the top of the pile comprising an oscillating agitator adapted to engage with the top of the pile, and means extending 85 from said agitator to the exterior of said combustion chamber for manipulating the same.
14. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile and also capable of being raised and lowered, and means extending 90 from said agitator to the exterior of said combustion chamber for oscillating and manipulating the same.
15. An incinerator comprising a combustion chamber adapted to receive a pile of refuse to be consumed, means for burning the pile of refuse from the top of the same downwardly, and means for removing the 95 ashes from the top of the pile comprising an oscillating agitator adapted to engage with the top of the pile, a vertical gear rack connected at its lower end with said agitator, a gear pinion meshing with said rack, an operating member connected with said pinion, and means for mounting said rack and pinion which permits the rack to move vertically independently of said pinion but 100 compels said rack and pinion to turn together about a vertical axis.
16. An incinerator comprising a combustion chamber adapted to receive a pile of refuse to be consumed, means for burning the pile of refuse from the top of the same down- 105
- 110
- 115
- 120
- 125
- 130

- wardly, and means for removing the ashes from the top of the pile comprising an oscillating agitator adapted to engage with the top of the pile, a vertical gear rack connected at its lower end with said agitator, a gear pinion meshing with said rack, an operating member connected with said pinion, and means for mounting said rack and pinion which permits the rack to move vertically independently of said pinion but compels said rack and pinion to turn together about a vertical axis, said mounting means comprising a bracket mounted on the upper part of said combustion chamber and having upper and lower bearings, bushings which turn in said bearings and in which said rack can slide vertically but is compelled to turn with the bushings, and a yoke which is arranged between said bushings and in which said rack slides but is compelled to turn therewith, and an operating shaft having its inner part journaled in said yoke and connected with said pinion and having its outer part arranged externally of said combustion chamber, and provided with a handle for manipulating the same, and said combustion chamber being provided with a segmental opening for receiving said operating shaft.
19. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile, a vertical gear rack connected at its lower end with said agitator, a gear pinion meshing with said rack, an operating member connected with said pinion, and means for mounting said rack and pinion which permits the rack to move vertically independently of said pinion but compels said rack and pinion to turn together about a vertical axis, said mounting means comprising a bracket mounted on the upper part of said combustion chamber and having upper and lower bearings, bushings which turn in said bearings and in which said rack can slide vertically but is compelled to turn with the bushings, and a yoke which is arranged between said bushings and in which said rack slides but is compelled to turn therewith, and an operating shaft having its inner part journaled in said yoke and connected with said pinion and having its outer part arranged externally of said combustion chamber.
20. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile, a vertical gear rack connected at its lower end with said agitator, a gear pinion meshing with said rack, an operating member connected with said pinion, and means for mounting said rack and pinion which permits the rack to move vertically independently of said pinion but compels said rack and pinion to turn together about a vertical axis, said mounting means comprising a bracket mounted on the upper part of said combustion chamber and having upper and lower bearings, bushings which turn in said bearings and in which said rack can slide vertically but is compelled to turn with the bushings, and a yoke which is arranged between said bushings and in which said rack slides but is compelled to turn therewith, and an operating shaft having its inner part journaled in said yoke and connected with said pinion and having its outer part arranged externally of said combustion chamber.
21. An incinerator comprising a combustion chamber adapted to receive a pile of refuse to be consumed, means for burning the pile of refuse from the top of the same downwardly, and means for removing the ashes from the top of the pile comprising an oscillating agitator adapted to engage with the top of the pile, a vertical gear rack connected at its lower end with said agitator, a gear pinion meshing with said rack, an operating member connected with said pinion, and means for mounting said rack and pinion which permits the rack to move vertically independently of said pinion but compels said rack and pinion to turn together about a vertical axis, said mounting means comprising a bracket mounted on the upper part of said combustion chamber and having upper and lower bearings, bushings which turn in said bearings and in which said rack can slide vertically but is compelled to turn with the bushings, and a yoke which is arranged between said bushings and in which said rack slides but is compelled to turn therewith, and an operating shaft having its inner part journaled in said yoke and connected with said pinion and having its outer part arranged externally of said combustion chamber.

said bracket and a locking lug arranged on said rack and adapted upon turning the latter in one direction to be disengaged from said hook and upon turning the rack in another direction to interlock said lug with said hook and prevent vertical motion of the rack.

21. An incinerator comprising a combustion chamber adapted to receive a pile of refuse to be consumed, means for burning the pile of refuse from the top of the same downwardly, means for removing the ashes from the top of the pile comprising an oscillating agitator adapted to engage with the top of the pile, and means for locking said agitator in its elevated position.

22. An incinerator comprising a combustion chamber adapted to receive the pile of refuse to be consumed, a burner adapted to direct a flame against the upper part of said pile, an agitator for removing the ashes from the top of said pile, elevating means for removing said agitator vertically and a flue which communicates with the upper end 25 of said chamber and which receives part of said elevating means.

23. An incinerator comprising a combustion chamber adapted to receive the pile of refuse to be consumed, a burner adapted to direct a flame against the upper part of said pile, an agitator for removing the ashes from the top of said pile, elevating means for moving said agitator vertically comprising a vertical gear rack which has its lower 35 end connected with said agitator, a gear pinion meshing with said rack, and a flue

connected with the top of said chamber and receiving the upper end of said rack.

24. An incinerator comprising a combustion chamber adapted to receive the pile of refuse to be consumed, a burner adapted to direct a flame against the upper part of said pile, an agitator for removing the ashes from the top of said pile, elevating means for moving said agitator vertically comprising a vertical gear rack which has its lower end connected with said agitator, a gear pinion meshing with said rack, a flue connected with the top of said chamber and receiving the upper end of said rack, and locking means for holding said agitator and rack in an elevated position.

25. An incinerator comprising a combustion chamber adapted to receive a pile of refuse to be burned and provided on its top 55 with a circular collar which forms a gas outlet and which has a segmental slot, and the top of said chamber having a recess leading from said slot to the exterior of the incinerator, a curved shutter sliding circumferentially on the periphery of said collar, an agitator adapted to engage with the top of the pile of refuse, and means for oscillating said agitator comprising an upright member connected with the agitator and arranged in 60 said collar, and a horizontally oscillating operating member projecting through said shutter and slot and operatively connected at its inner end with said upright member.

In testimony whereof I affix my signature.

EDWARD KENER, JR.
